Joseph Lemberg, New York, N. Y.

Application December 11, 1942, Serial No. 468,693

7 Claims. (Cl. 89—37)

This invention aims to provide a piece of ordnance including novel means whereby a plurality of gun barrels may be raised and lowered bodily, swung in a vertical plane and rotated about a vertical axis, novel means being supplied for holding the barrels in adjusted positions and for firing the barrels at the will of an operator. A further object of the invention is to supply a piece of ordnance so constructed that rapid discharge may be effected in a plurality of directions at the will of an operator.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in side elevation, a device constructed in accordance with the invention, parts being broken away;

Fig. 2 is a rear end elevation, circuits being in diagram;

Fig. 3 is a top plan;

Fig. 4 is a transverse section showing most of the raising and lowering mechanism in top plan;

Fig. 5 is a section on the line 5—5 of Fig. 3;

Fig. 6 is an elevation disclosing one of the adjustable props;

Fig. 7 is a section on the line 7—7 of Fig. 4;

Fig. 8 is a rear elevation showing a modification.

The piece of ordnance forming the subject matter of this application includes an elongated base 1, which may be carried on wheels 2. Longitudinal tracks 3, such as channels, are secured to the base 1, and have upturned ends 4. An inverted, U-shaped, upstanding keeper 5 is secured to the base, near the rear end thereof.

The numeral 6 designates a transverse axle, disposed above the base 1 and carrying wheels 7 adapted to roll along the tracks 3 of the base. The numeral 8 marks a hollow guide, including a tubular body 9 having at its upper end, an outstanding flange 21, whereunto an annular top 10 is attached by means of securing elements 11. The lower end of the body 9 of the guide 8 is re-

ceived in a recess 12, formed in the axle 6, and the axle has a transverse opening 14, located at the bottom of the recess 12. Securing elements 15 pass through the bottom of the body 9 of the guide 8, and hold the guide in the recess 12.

The opening 14 of the axle 6 receives the horizontally enlarged forward end 16 of a rearwardly extended arm 17, one or more of the securing elements 15 passing through the said end of the arm, to hold the arm assembled with the axle 6.

The rear end of the arm 17 is received in the guide 5 on the base 1. Intermediate its ends, the arm 17 is supplied with a depending bracket 18, whereon wheels 19 are mounted to turn, the

wheels being adapted to roll along the base 1. A retractile spring connection 20 is extended rearwardly from the bracket 18 of the arm 17 and is anchored at its rear end upon the base 1. The spring 20 should be of considerable strength.

20 Referring especially to Fig. 7, a hollow plunger 22 is mounted for right line reciprocation and for rotation in the top 10 of the guide 8. A circumscribing shoulder 23, preferably a ball race, is secured at 31 to the lower portion of the plunger 22, and carries anti-friction balls 24, adapted to roll in contact with the inner surface of the body 9 of the guide 8.

The upper wall 25 of the plunger 22 has an outstanding rim 26, the upper wall carrying 30 transversely spaced upper ears 27, between which is disposed a depending ear 28 on an elongated bed 29, having a recess 32 in its upper surface. A pivot member 30 connects the ears 27 with the ear 28. Hangers 33 are secured at 34 to the rear end of the bed 29 and support a step 35. A retractile spring connection 36 is disposed to the rear of the guide 8 and has its upper end secured at 37 to the bed 29, the lower end of the spring being secured at 38 to the arm 17, in advance of the wheel 19.

A bearing 40 is secured to the forward portion of the bed 29, and in the bearing, a depending socket 39 of tubular form is mounted for rotation. The socket 39 is provided with oppositely disposed, vertically elongated slots 41. The numeral 43 designates a castor wheel, adapted to cooperate with the base 1, and journaled on a shank 44, mounted for vertical reciprocation in the socket 39, the shank having laterally projecting guide pins 42, received slidably in the slots 41 of the socket 39. A compression spring 45 is disposed within the socket 39 and is interposed between the upper wall of the socket and the upper end of the shank 44, which is slidably mounted. An elongated handle 46 is secured at 47 to one

edge of the bed 29, and extends backwardly, as far as desired.

Angle brackets 48 are secured to the axle 6. The numeral 49 marks a transverse support, provided with a circular opening 50 in which the plunger 22 is mounted for rotation. In its upper surface, the support 49 is supplied with an annular seat 51, receiving an anti-friction bearing 52, upon which the rim 26 of the plunger 22 rests.

A raising and lowering means for the plunger 22 is provided, and includes screws 53, right and left hand threaded into the support 49 and into the brackets 48 which are secured to the axle 6. The screws 53 may be manipulated by hand wheels 54 on their upper ends, or in any other appropriate way.

Longitudinally extensible props 55 are supplied, each prop including an upper member 56, mounted to swing from front to back on the securing element 47 for the handle 46 that is at the rear of the bed 29, and on another securing element which will be referred to hereinafter. The upper members 56 of the props 45 have elongated slots 57, as Fig. 6 shows.

Each prop 55 comprises a lower member 58, having lugs 59 received slidably in the slot 57 of the corresponding upper member 56. A holding device is supplied, for retaining each prop 55 at a predetermined length. The holding device may be a headed bolt 60, carried by the lower member 58, and provided with a lever nut 61.

A jacket 62 is mounted in the recess 32 of the bed 29, and may be constructed in any desired way to bring about a cooling of the barrels hereinafter mentioned. If water is used in connection with the jacket 62, as indicated at 63, the jacket will have the usual water connections 64. The jacket is held on the bed 29 in any selected way, for instance, by means of straps 65, fastened to the bed by securing elements 66.

The jacket 62 is disposed about a central barrel 67, and about other barrels 68, arranged around the barrel 67. The bore of the barrel 67 preferably is greater than the bore of the barrels 68. The breech block for the barrel 67 is designated by the numeral 69, and the breech blocks for the barrels 68 are indicated at 70.

The jacket 62 is provided on its upper surface with a collar 71, in which is located a bearing cup 72. The lower end of a post 73 is received for rotation in the bearing 72, the post having a rearwardly projecting handle 74. The post 73 is mounted to turn on a shaft 75 carried by the jacket 62. A nut 76 is threaded on the upper end of the shaft 75 and engages the upper portion of the post 73, within a recess 77 which is formed in the post. The upper end of the post 73 carries a standard 78, on which a telescope 79 is mounted. At its upper end, the post 73 is supplied with a forwardly presented offset 80.

Auxiliary barrels 83 are disposed on opposite sides of the post 73, the breech blocks of the barrels being marked by the numeral 81. Each barrel 83 has a depending handle 82. The trunnions 84 of the barrels 83 are mounted to rock, individually, about a substantially horizontal axis, in the offset 80 of the post 73.

A switch S is provided, and may be located at any desired distance from the mechanism hereinbefore described. The switch S includes a dial 85, carrying a circle of contact points 86, adapted to be engaged one after another by a switch arm 87, mounted to swing over the surface of the dial 85.

A conductor 88 is connected electrically with

the switch arm 87, and is grounded as shown at 89, a source 90 of electrical energy being interposed in the conductor. From each of the contact points 86, a conductor 91 leads to the firing mechanism of one of the breech blocks 79 of the barrels 68. The firing circuit is grounded through the gun frame.

The circle of contacts on the dial 85 includes points 93, and a point 92. The contact points 93 are connected by conductors 94, to firing mechanisms in the breech blocks 81 of the barrels 83. The contact point 92 is joined by a conductor 95 to the firing mechanism of the breech block 69 of the barrel 67.

Owing to the simple nature of the diagrammatic portion of Fig. 2, an extended description of the firing operation is not necessary. It will be observed that the operator has under his control, a means for firing any of the barrels 83, 68 and 67, and the firing operation may be carried out as rapidly or as leisurely as the operator may desire.

Referring to Fig. 8, parts hereinbefore described are designated by numerals already used, with the suffix "a."

Instead of having a switch including a remote dial, such as the dial 85 of Fig. 2, there are contacts 96 on the breech blocks 69a, and the jacket 62a carries a contact 97 for the central breech block 69a. The contact 97 is connected to the firing mechanism of the central breech block 70a by a conductor 98. At 99 there is shown a switch arm pivotally mounted on the breech block 70. The switch arm 99 is adapted to engage the contacts 97 and 96, one at a time. To the switch arm 99 is connected electrically, a conductor 100, which is grounded as shown at 101, a source 102 of electrical energy being interposed in the conductor 100. The ground for the firing mechanism of the breech block 69 is designated by the numeral 103.

When the switch arm 99 is on the contact 97, there will be established a circuit including the ground 101, the source of energy 102, the conductor 100, the switch arm 99, the firing mechanism of the breech block 70a, and the ground 103, the central barrel, corresponding to the barrel 67 of Fig. 1 being fired. In a similar manner, when the switch arm is on one of the contacts 96, the corresponding barrel 68 of Fig. 1 will be fired, the ground 103 being common to the firing mechanisms of the several breech blocks 69a.

The firing mechanisms of the breech blocks 81a, which are individual to the barrels 83 of Fig. 1, are grounded at one side, as shown at 105. When the switch arm 99 is on a contact 104, one of the auxiliary barrels 83 of Fig. 1 will be fired, and when the switch arm is on the other contact 105, the corresponding auxiliary barrel will be fired. It is believed that it is unnecessary to trace out the simple circuits involved.

Any suitable recoil check may be used, the present invention making no contribution to that art. When the recoil mechanism produces a forward or return movement (as is common), that movement is cushioned by the spring 20. Since the arm 17 is received in the keeper 5, the arm tends to guide the structure in its forward and rearward movements on the track 3. Since the props 55 are adjustable as to length, they will support the bed 29 and associated parts in a horizontal position, or in a position in which the barrels are inclined with respect to the vertical. Assuming that the props 55 are of the lengths shown in Fig. 1, the barrels, such as the

barrels 68 and 67, may be swung downwardly at their forward ends, and if the props 55 are adjusted to a shorter length than that shown in Fig. 1, the barrels 68 etc., along with the bed, may be swung upwardly. The point of swinging movement of the bed 29 and associated parts, vertically, is the pivot member 30 of Fig. 7, the up and down swinging movement being brought about through the instrumentality of the handle 46. The piece is heavier ahead of the pivot element 30 than it is behind the pivot element, and the spring 36 aids in securing a counterpoise. Upon recoil, the structure moves rearwardly, the wheel 43 rolling on the base 1, and the wheels 19 rolling on the base. The wheels 7 roll on the tracks 3.

In order to raise and lower the bed 29 and parts carried by it, bodily, the screws 53 are rotated by means of the hand wheels 54, the threading at 53 cooperating in an obvious way with the brackets 48 and with the support 49. The plunger 22 moves upwardly and downwardly without binding, owing to the contact between the ball bearings 24 and the body 9 of the guide 8. Upward movement of the bed 29 and associated parts is limited when the race 23 on the plunger 22 comes into contact with the top 10 of the guide 8.

The bed 29 and associated parts may be swung in azimuth by means of the handle 46, the anti-friction bearings 24 and 52 facilitating such an operation.

Through the instrumentality of the handle 74, the post 73 may be rotated about a substantially vertical axis, the barrels 83 moving in azimuth. The handles 82 constitute means whereby vertical swinging movement may be imparted to the barrels 83, individually.

The springs 36 and 20 of Fig. 1 constitute draw connections. The bed 29 and the jacket 62 form a carrier for the auxiliary barrels 83 and attendant parts.

Having thus described the invention, what is claimed is:

1. In a piece of ordnance, a base, a guide supported by the base for movement longitudinally thereof, a plunger mounted on the guide for raising and lowering and for rotation about a substantially vertical axis, means for raising and lowering the guide, a bed disposed above the plunger, a barrel carried by the bed, means for mounting the bed on the plunger for vertical swinging movement, a rearwardly extended arm fixed with respect to the guide, a keeper on the base and receiving the arm slidably, an upright retractile connection joined to the arm and to the bed and disposed to the rear of the means for mounting the bed on the plunger, a retractile connection extended longitudinally of the arm and having its forward end connected to the arm, its rear end being connected to the bed, means under the control of an operator for rotating the plunger to swing the bed laterally, and for swinging the bed vertically.

2. In a piece of ordnance, a base, a guide supported by the base for movement longitudinally thereof, a plunger mounted on the guide for raising and lowering and for rotation about a substantially vertical axis, a bed disposed above the plunger, a barrel carried by the bed, means for mounting the bed on the plunger for vertical swinging movement, a transverse support wherein the plunger is rotatable, members fixed with respect to the guide and located on opposite sides of the guide, raising and lowering mecha-

nisms assembled with said members and with the terminal portions of the support, thereby to adjust the support, the plunger, the bed and the barrel vertically, a longitudinally extensible prop disposed to the rear of the means for mounting the bed on the plunger and extended between the base and the bed, means under the control of an operator for rotating the plunger to swing the bed and the barrel laterally, and for swinging the bed and barrel vertically.

3. In a piece of ordnance, a base, a guide supported by the base for movement longitudinally thereof, a plunger mounted on the guide for raising and lowering and for rotation about a substantially vertical axis, a bed disposed above the plunger, a barrel carried by the bed, means for mounting the bed on the plunger for vertical swinging movement, a transverse support wherein the plunger is rotatable, members fixed with respect to the guide and located on opposite sides to the guide, raising and lowering mechanisms assembled with said members and with the terminal portions of the support, thereby to adjust the support, the plunger, the bed and the barrel vertically, a longitudinally extensible prop disposed to the rear of the means for mounting the bed on the plunger and extended between the base and the bed, a rearwardly extended arm fixed with respect to the guide, a keeper on the base and receiving the arm slidably, an upright retractile connection joined to the arm and to the bed and disposed to the rear of the means for mounting the bed on the plunger, a retractile connection extended longitudinally of the arm and having its forward end connected to the arm, its rear end being connected to the bed, means under the control of an operator for rotating the plunger to swing the bed and the barrel laterally, and for swinging the bed and the barrel vertically.

4. In a piece of ordnance, a base, tracks on the base, an axle, wheels carried by the axle and movable along the tracks, an upright guide secured to the axle, a plunger mounted on the guide for vertical adjustment and for rotation, means for raising and lowering the plunger, a bed, a barrel carried by the bed, means for mounting the bed on the plunger for vertical swinging movement, a wheel frame disposed ahead of the guide including a shank, means for mounting the bed for up and down movement on the shank, means for yieldably resisting the downward movement of the bed with respect to the shank, a wheel carried by the frame and engaging the base, and a longitudinally extensible prop located to the rear of the guide and extended between the bed and the base.

5. In a piece of ordnance, a tubular guide, means for mounting the guide in a substantially vertical position, a support disposed above the guide, a top member on the guide, an inwardly projecting, annular flange on the top member, a plunger mounted to move vertically in the flange, and to rotate in the flange and in the support, the plunger being provided near its upper end with an outstanding rim which overlaps the support, an anti-friction bearing between the rim and the support, an outstanding race member secured about the plunger near the lower end thereof, an anti-friction bearing carried by the race member and engaging the inner surface of the guide, the race member being engageable with the flange, to limit the upward movement of the plunger, means engaged with the support for raising and lowering the plunger, a barrel, and

means for mounting the barrel movably on the plunger.

6. In a piece of ordnance, a tubular guide, means for mounting the guide in a substantially vertical position, a support disposed above the guide, a top member on the guide, an inwardly projecting, annular flange on the top member, a plunger mounted to move vertically in the flange, and to rotate in the flange and in the support, the plunger being provided near its upper end with an outstanding rim which overlaps the support, an anti-friction bearing between the rim and the support, an outstanding race member secured about the plunger near the lower end thereof, an anti-friction bearing carried by the race member and engaging the inner surface of the guide, the race member being engageable with the flange, to limit the upward movement of the plunger, a bed disposed about the plunger, means for connecting the bed movably with the plunger, a barrel carried by the bed, fixed members located on opposite sides of the

guide, and raising and lowering screws right and left hand threaded into the fixed members and into the terminal portions of the support.

7. In a piece of ordnance, a guide, a plunger mounted to move vertically on the guide and to rotate with respect thereto, mechanism under the control of an operator for moving the plunger vertically, a carrier pivoted to the plunger for vertical swinging movement, means under the control of an operator for imparting vertical swinging movement to the carrier, and for rotating the plunger, a substantially vertical shaft on the carrier, a post mounted to rotate on the shaft, about the vertical axis thereof, barrels disposed on opposite sides of the post and having substantially horizontal trunnions mounted to rock in the post, whereby the barrels may be swung vertically, one at a time, a substantially vertical handle on each barrel, and a substantially horizontal handle on the post.
